HERBERT G. BEEDE, OF PAWTUCKET, RHODE ISLAND.

MOUNT FOR SPINDLES OF SPINNING OR TWISTING MACHINES.

Application filed November 6, 1914. Serial No. 870,606.

To all whom it may concern:

Be it known that I, HERBERT G. BEEDE, a citizen of the United States, residing at Pawtucket, in the county of Providence and State of Rhode Island, have invented certain new and useful Improvements in Mounts for Spindles of Spinning or Twisting Machines, of which the following is a specification.

This invention relates to improved means for mounting spindles of the floating or flexible type, and it consists essentially of a spindle-blade provided with a driving whirl, a non-revolvble bolster having said blade freely revolvble therein, a stationary hollow base having its upper portion recessed or chambered to receive and support the bolster, said base portion being enveloped by the driving-whirl, and a ball-bearing having its inner race rigidly fixed to the blade and the outer race seated in said bolster recess and capable of limited frictional rotary movement therein, constructed and arranged whereby the ball-bearing is normally submerged in the oil or lubricant. By means of my improved construction of spindle mounting the spindle is practically self-aligning in that it automatically adapts itself to varying gyratory conditions of speed, load and band pull; the weight or thrust of the revolving parts longitudinally is borne by the positioned ball-bearing, the latter at the same time also neutralizing the lateral or radial pulling force of the band.

In the present improvement the bolster is extended and enlarged so that the ball-bearing is positioned at a point practically opposite or midway of the whirl. As thus constructed the device is rendered more sensitive in correcting variations in the speed, &c., of the spindle. The oil reservoir extends above the top of the bolster thereby ensuring the submergence of the ball-bearing in the lubricant. The spindle mount is simple, not liable to become accidentally inoperative, and the cost of manufacture is materially reduced.

In the accompanying sheet of drawings Figure 1 is a longitudinal sectional view, taken substantially through the center of the device, and Fig. 2 is a side elevation of the bolster and a portion of the blade showing a slightly modified form; the upper and lower end portions of the bolster, in-

cluding the ball-bearing, being represented in section.

Again referring to the drawings, *a* indicates the bolster-case recessed at its upper end and arranged to be secured to a bolster-rail in a well-known way, *b* is the non-revolvble chambered or recessed bolster removably mounted in the bolster-case, *c* is the central steel spindle blade freely revolvble in the bolster, *d* is a ball-bearing located in the recessed portion of the bolster and engageable with the latter and said blade, and *f* indicates the band whirl fixed to the blade, said whirl having an open recess formed in its lower end.

The said bolster-case *a* is hollow or tubular, its upper portion *a*¹ being enlarged and provided with a comparatively deep, centrally bored recess *a*² terminating at its lower end in an inwardly extending circular seat *a*³. The bolster-case is elongated and provided with a central chamber forming an oil well or reservoir *a*⁴ in open communication with an outer branch oil-tube or member *a*⁵ having its mouth substantially level with the upper end of the bolster, thereby ensuring the submergence of the bolster and its ball-bearing in the oil or lubricant.

The bolster *b* is mounted in the said bore or well *a*⁴ of the bolster-case; the upper or head portion *b*¹ of the bolster is enlarged and forms a bottom shoulder *b*² capable of vibrating slightly sidewise on the fixed supporting seat *a*³ of the bolster-case. The said cylindrical portion *b*¹ is also provided with a recess or socket *b*³ adapted to receive the ball-bearing *d*, later described. The outer surface of the bolster head may be provided with longitudinal grooves *b*⁴, *b*⁶, the former being cut comparatively deep and arranged to receive the free end of a locking pin *p* fixed in the seat *a*³ to prevent the bolster from turning. Holes *b*⁶, extending laterally through the wall of the recessed portion of the bolster assist in the oil circulation.

The steel spindle-blade *c* is or may be constructed substantially as usual, and having its lower portion tapering and revolvably mounted in the bolster. The bottom end *c*¹ of the blade may have a running fit in the corresponding part of the bolster, to control the lateral action of the bolster, that is, to compel the bolster to move laterally with

the spindle and thereby move against the cushioning effect of the oil, as represented in Fig. 1, or the blade may be revolubly supported in a step or socket c^4 as shown in 5 Fig. 2.

The belt or band-driven whirl f is fixed to the blade c about midway thereof; the whirl, in connection with the blade is arranged or adapted to support a bobbin as common.

10 The whirl is recessed on its lower side or end, as at f^1 to freely receive the said annular extension b^1 of the bolster-case.

The inner race d^1 of the ball-bearing d is fixed to the blade, a shoulder c^3 of the lat-

15 ter, in connection with a spaced collar i , serving to positively maintain the race in position longitudinally on the blade; the outer race d^2 is capable of angular movement in the recess b^3 of the bolster, the rate of

20 movement or "creeping" action of the outer race, however, being very small. The lower edge of the race d^2 is supported on the bottom of the bolster recess b^3 when the weight or thrust of the blade, whirl, etc. are dis-

25 posed as represented in Fig. 1, and when the blade is supported in a step or socket c^4 , as indicated in Fig. 2, the race d^2 may not bear upon the bottom of the recess b^3 .

In so-called flexible or loose bolster spin- 30 dles as heretofore constructed the upper or bolster bearing has been an elongated bearing, while the lower or step bearing has been very short, and in some cases with practically no lateral support for the lower end of the 35 spindle.

In such spindles means are provided to hold the loose bolster against rotation with the spindle. With such constructions, however, there is a continual tendency to rotate 40 the bolster with the spindle, which, in connection with the restraint against turning of the spindle, causes a reaction upon the spindle itself and thus has the effect to produce chattering of the spindle. With the 45 present construction, in which the upper bearing is a ball bearing and thus a very short bearing, the spindle runs free, there is no tendency to rotate the bolster with the spindle, and consequently no reaction on the 50 spindle itself, and chattering is avoided. So also the bolster is left free to perform its function as a loose bolster, that is, to absorb vibrations through its oil packing. Moreover, in the present construction with 55 its short upper bearing, the lower or step bearing is made of considerable length and this elongated step bearing assists materially to support the spindle in proper relation to the bolster, and also serves to facilitate the 60 employment of such a short upper bearing as is furnished by the ball bearing employed. With the present construction the self righting of the spindle under an unbalanced load is materially facilitated.

I claim:—

1. A mount for spindles comprising a bolster case having a centrally recessed upper portion, a recessed non-revoluble bolster loosely supported in said bolster-case, the recessed portion of the bolster mounted in the said recess of the bolster-case, a revoluble spindle-blade extending longitudinally in the bolster, a ball-bearing supported in the recessed portion of the bolster, the inner race of the ball-bearing fixed to the blade, and a whirl also secured to the blade, said whirl having an inverted recess into which the upper portion of the bolster-case extends.

2. In a device of the character described, the combination of a bolster-case having its upper part enlarged transversely and provided with a longitudinal recess or chamber, a bolster having its upper portion in said recess, said portion of the bolster also being recessed, a spindle-blade, a ball-bearing located in the bolster recess and having members of said bearing engaging both the blade and the encircling wall of the socket or recess, and a recessed whirl fixed to said blade, the relation of the said parts to one another being such that a plane cutting substantially through the center of the whirl transversely extends through the corresponding portions of said bolster-case, 90 bolster, ball-bearing and spindle-blade.

3. A spindle support consisting of a bolster-case having a recessed enlargement in its upper portion, a bolster-support in said recessed portion of the bolster-case, said bolster also having its upper portion provided with a recess, a ball-bearing fitted in the bolster recess, said ball-bearing having balls interposed between inner and outer race-members, a vertical spindle-blade extending 100 longitudinally above and below said recesses and through said ball-bearing, the inner race-member being fixed to the spindle-blade, a whirl secured to the spindle-blade, said whirl having a recess in its inside to encircle 110 the enlarged portion of the bolster-case, and means for keeping the ball-bearing submerged in a lubricant.

4. The combination, with a spindle, of a bolster-case, a bolster loosely mounted in 115 said bolster-case and an upper bearing for said spindle consisting of a ball-bearing between said bolster and said spindle.

5. The combination, with a spindle, of a bolster-case, a bolster loosely mounted in 120 said bolster-case, an upper bearing for said spindle consisting of a ball-bearing between said bolster and said spindle, and an elongated step-bearing for said spindle formed in the lower end of said bolster.

6. The combination of a bolster-case, a bolster loosely mounted in said case, a spindle having a whirl arranged to surround the

upper end of said bolster, and an upper bearing for said spindle consisting of a ball-bearing between said bolster and said spindle, said ball-bearing being located in line with 5 the whirl of said spindle.

7. The combination of a spindle, a supporting base, a ball bearing supported by said base and supporting said spindle, and an element connected with the spindle 10 adapted to receive a driving band and arranged in the same plane with said ball bearing, the step or foot of the spindle being capable of lateral cushioned movement.

8. A spindle comprising a blade, a whirl 15 having provisions for receiving a driving band associated therewith for rotating the same, and a ball bearing in the line of pull of such band supporting said blade, the blade having a step bearing arranged with 20 capacity for cushioned lateral movement to permit alinement or centering of the center of gravity with the axis of rotation of the spindle blade with a bobbin thereon.

9. A spindle comprising in combination 25 a blade, means for transmitting thereto the pull of the driving band, a ball bearing in the line of pull of such band supporting said blade and a step bearing for the end of the blade below said ball bearing, the step bearing 30 being mounted with provision for lateral cushioned movement.

10. A spindle comprising a base having a hollow depending portion, a step bearing contained in said depending portion of such 35 size as to be movable laterally therein at its lower end, a blade extending into said step bearing, a ball bearing above the step bearing supporting the blade, a driving pulley surrounding and in the same plane with said bearing connected to the blade, and a body 40 of oil contained in said depending part and surrounding the step bearing and providing a cushion to impede the lateral movements thereof.

11. A spindle comprising in combination, 45 a blade, a ball bearing surrounding and supporting said blade, the outer member of said bearing being a sleeve rising above the bearing and providing an oil chamber, and a supply tube for oil entering said chamber 50 and having its external orifice above the ball bearing, whereby to maintain the bearing submerged in oil.

12. A spindle having a lateral ball bearing 55 and means for oiling and retaining oil at a level above the said ball bearing; the lower end of the spindle being capable of lateral cushioned movement.

13. A spindle comprising a blade, a ball

bearing surrounding the blade at a material 60 distance from either end thereof, and means for supplying and maintaining a body of oil at and above said bearing, the lower end of the blade being capable of lateral movement. 65

14. A spindle having a ball bearing and external means for oiling and capable of retaining oil at a level above the said ball bearing, the lower end of the spindle being capable of lateral cushioned movement. 70

15. A spindle, a whirl thereon having means to take the pull of a driving band, a ball bearing for the spindle at or near the center of the band pull, and means for oiling and retaining oil at a level above the 75 ball bearing; the lower end of the spindle being capable of lateral cushioned movement.

16. A spindle comprising a blade, a whirl 80 on said blade having means to take the pull of a driving band, a ball race fitted to said blade having a ball bearing at or near the center of the band pull, means for oiling and retaining oil at the highest oiling level and above the ball bearing; the lower end of the 85 spindle being capable of lateral cushioned movement.

17. A spindle comprising a base having a depending socket portion closed at its lower end, a blade contained in said socket portion and rising from the base, and a ball bearing supporting said blade and located above the lower end of the blade; said lower end being constructed of smaller diameter 90 than the interior of said socket portion and 95 being movable laterally therein to bring the center of gravity and rotational axis of the spindle into coincidence.

18. A spindle comprising a base having a depending socket portion closed at its 100 lower end, a blade contained in said socket portion and rising from the base, and a ball bearing supporting said blade and located above the lower end of the blade; said lower end being constructed of smaller diameter 105 than the interior of said socket portion and being movable laterally therein to bring the center of gravity and rotational axis of the spindle into coincidence, and a body of fluid 110 in said socket member for damping the lateral movements of said lower end.

In testimony whereof I have affixed my signature in presence of two witnesses.
